UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR ORNAMENTAL PANELS ON ARTICLES OF BUILDERS' HARDWARE.

SPECIFICATION forming part of Design No. 12,855, dated April 11, 1882.

Application filed February 23, 1882. Term of patent 7 years.

To all whom it may concern:

Be it known that I, GEORGE S. BARKENTIN, a citizen of the United States, residing at New Britain, in the county of Hartford and State 5 of Connecticut, have invented and produced a new and original Design for Ornamental Panels on Articles of Builders' Hardware, of which the following is a specification, reference being had to the accompanying drawing, forming part thereof.

The drawing shows a perspective view of my design as applied to a hinge.

In practice I intend to apply the leading features of this design, hereinafter specified, 15 to a full line of builders' hardware, including the face-plate or front for the latch and lock, the key-hole, and knob-escutcheon, the knob, and other articles.

The leading feature of my design consists 20 of the ornamentation of the ground-work or sunken surface of the panels by a series of conventional flowers, having circular outlines, and made to overlap each other in a manner which might be called "shingled." I have herein 25 illustrated these flowers as composed, first, of a small sunken center, then a small sunken circle inclosing said center, from which circle sunken lines extend outward to form the flower, and bordering each conventional flower 30 is a sunken circle, or, rather, what would be a circle if wholly exposed, the same constituting a circular outline for each flower. The overlapping or shingling of a series of these flowers of course prevents the circular outline from 35 being exposed to view, so as to show many complete articles. Each of the hinge-leaves is bordered by a raised border, and the ground-work ornament herein described is for the sunken surface of said panel. The tips A A 40 for the hinges I form with a square portion, each side of which has a sunken panel, the ground of which is ornamented, as above described. In all cases, whether the design is applied to a hinge or other articles of builders' 45 hardware, I intend to make the design by de-

pressions and elevations in the surface of the metal—as, for instance, by casting, engraving, or stamping, and to inclose the same by a raised border, to form a panel, the contour of which panel may be round, rectangular, or other desired form. 50

Another leading feature of my design is the relief ornaments *a a* at one or more points within the main border of the panel, and covering portions of the ground ornamentation hereinbefore described, and leaving portions of it exposed by the sides of said relief ornaments. The face of the latter is intended to be flush with the face of the main border, which forms the panel. 55

The particular design for the ornaments *a a* I intend to make the subject of an independent application, and other relief ornaments may be substituted therefor without changing this part of my design, the essential feature 65 of which is a panel inclosing a relief ornament whose face is flush with the border of the panel, and upon the sides of which ornament is the sunken ground, composed of overlapping conventional flowers, hereinbefore described. 70

I claim as my invention—

1. The design for the ornamental panels on articles of builders' hardware, herein shown and described, the same consisting of a series of overlapping conventional flowers, with circular 75 outlines on the ground-work of the panel.

2. The design for the ornamental panels on articles of builders' hardware herein shown and described, the same consisting of the raised border of the panel, one or more relief ornaments whose face is flush with that of said border, and the series of overlapping conventional flowers, with circular outlines on the ground by the side of the relief ornaments, all 80 inclosed by the border of the panel.

GEORGE S. BARKENTIN.
